ROBERT SUCZEK, OF PHILADELPHIA, PENNSYLVANIA, ASSIGNOR TO C. H. WHEELER
MANUFACTURING COMPANY, OF PHILADELPHIA, PENNSYLVANIA, A CORPORATION
OF PENNSYLVANIA.

CONDENSATE AND AIR REMOVING APPARATUS.

1,282,978.

Specification of Letters Patent.

Patented Oct. 29, 1918.

Original application filed May 7, 1917, Serial No. 167,061. Divided and this application filed December 18, 1917. Serial No. 207,744.

To all whom it may concern:

Be it known that I, ROBERT SUCZEK, a subject of the Emperor of Austria-Hungary, residing in the city of Philadelphia, county 5 of Philadelphia, and State of Pennsylvania, have invented certain new and useful Improvements in Condensate and Air Removing Apparatus, of which the following is a specification.

10 My invention relates to apparatus for removing condensate and air or other uncon- densable gas or vapor from a condenser, or from kindred apparatus.

My invention resides in centrifugal pumping means for removing both condensate and air or vapor from a condenser and comprising impeller structure part of which removes condensate and another part of which removes air or vapor, with structure pro- 20 viding for admission of additional water or liquid.

My invention resides in structure of the character above referred to which is particularly suitable for use in connection with a 25 surface condenser, whereby upon decrease in condensate the additional water maintains the operation of the apparatus. And in such relation automatic means are provided for controlling admission of the ad- 30 ditional water in response to changes in amount of condensate.

This application is a division from my application Serial Number 167,061, filed May 7, 1917.

35 For an illustration of one of the various forms my invention may take, reference is to be had to the accompanying drawing, in which:

Figure 1 is a vertical sectional view, some 40 parts in elevation, through apparatus embodying my invention.

Fig. 2 is a sectional view taken on the line 2-2 of Fig. 1.

Referring to the drawing, A represents 45 the shell of a surface condenser of any well known structure, the details of construction of which are not shown. The steam to be condensed is admitted through the passage K, and when condensed collects as condensate in the bottom of the shell A and within the chamber or hot well F communicating with the suction n of the impeller I₁. The impeller I₁ comprises the vanes v₁, between which are passages communicating with the 55 suction n and delivering into the volute or discharge casing v₄. With the spaces be-

tween the vanes v₁ communicate the passages between the vanes v of the impeller I₂. The impellers I₁ and I₂ are integral or form a common impeller structure driven by the 60 shaft S driven by any suitable motor, not shown, and having a bearing at B. The inlet or suction for the impeller I₂ is the tubular extension p communicating with the chamber o. Surrounding the tubular exten- 65 sion p is the chamber r to which water or other suitable liquid is delivered by the pipe s having therein a valve t secured upon a pivot w rotated through suitable angle by the link x secured thereto at one end and pivoted at its other end at y to a link z which is pivoted at its other end at a₁ to the link b₁ secured upon the pivotal shaft c₁ extending through a vacuum tight bearing or stuff- 70 ing box in the condenser shell. To the shaft c₁ is secured the arm d₁ carrying at its end the float e₁ resting upon the condensate whose level is indicated by the dotted line b₂. The links x, z, and b₁ need not be of the proportions and sizes indicated, but are to 75 be taken merely as a diagrammatic representation of means causing pivotal movement of the valve t in response to movement of the float e₁ with changes in the condensate level b₂.

E and E₁ are ejectors of any suitable construction, actuated preferably by steam or other elastic motive fluid. These ejectors are connected in series with each other through the intermediate connecting pipe j controlled 90 by valve k. The pipe j communicates also through the valve m with the interior of the chamber o. The suction chamber of the ejector E communicates with the interior of the condenser shell A through the passage f, 95 through which the air or uncondensable vapors to be compressed pass outwardly to the ejector E.

Communicating with the water chamber, r, are openings or passages g₁ in the left hand 100 wall of the impeller I₂, as indicated in dotted lines in Fig. 1. These passages g₁ are disposed between neighboring vanes v and v₁, as indicated in Fig. 2, and communicate with the passages of the impeller I₁ between 105 its vanes v₁.

The operation is as follows:

In starting, a suitable degree of vacuum within the condenser shell A is produced by the simultaneous operation of the ejectors 110 E and E₁ in series, the valve k being open for this purpose and the valve m closed.

When a suitable degree of vacuum is attained, the valve m is opened and the valve k closed, and the supply of motive fluid to the second ejector E_1 is discontinued, the 5 ejector E continuing, however, to extract air or uncondensable vapors from within the condenser shell and to deliver the same into chamber o .

The shaft S is rotated at suitable speed; 10 the steam to be condensed enters the condenser at K and is condensed therein and collects in the hot well F , from which it is removed by the impeller I_1 , which delivers it at higher pressure, as atmospheric, into 15 the discharge casing or volute V_1 .

The ejector E withdraws air or uncondensable vapors from the condenser shell A and delivers it through the pipe j and valve m into the chamber o , and thence through 20 the tubular projection p into the impeller I_2 , which by centrifugal action further raises the pressure of the air or uncondensable vapors and the motive fluid from ejector E and throws it outwardly into the condensate in the spaces between the vanes v_1 25 in the impeller I_1 , where the condensable vapors and motive fluid from the ejector E are condensed by coming into contact with the condensate; and air and uncondensable vapors then move with the condensate 30 through the impeller I_1 , which increases their pressure, and the mixture of water and air or uncondensable vapors is delivered into the discharge casing V_1 at atmospheric 35 pressure or higher, or at any other suitable pressure.

By this action the air or uncondensable vapors are compressed in successive stages from the low pressure existing within the 40 condenser shell to atmospheric pressure or other suitably higher pressure, the ejector E causing the preliminary compression and the pump structure completing the compression.

45 Inasmuch as with a surface condenser the condensate is strictly condensate, that is, only condensed steam, there is, relative to a jet condenser of the same capacity, a smaller amount of water to be removed, since in a 50 jet condenser not only the condensate but also the condensing water with which the condensate is mixed must be removed. The condensate is removed, as described, by the impeller I_1 ; but in case the amount of steam 55 to be condensed and entering at K be diminished, as in case of light load upon the engine or other device exhausting into the condenser A , the amount of condensate might be so much diminished that the extent of submergence of the impeller I_1 , that 60 is, the distance from the condensate level b_2 to the impeller, is so reduced that the pump removes a less amount of condensate; and with less amount of water flowing through 65 the impeller I_1 , the assistance rendered by

it to the ejector E in removing the air or uncondensable vapors is diminished and would occasion an undesired rise in pressure within the condenser shell. This disadvantage is overcome, however, from the fact that as 70 the condensate diminishes, the float e_1 descends, and through the system of links described opens or further opens the valve t , to allow or increase inflow of water from any suitable source through the pipe s into 75 the chamber r , from which it passes through the aforementioned passages g_1 and is delivered into the impeller I_1 into the passages between its vanes v_1 , thus affording additional water supply and maintaining the 80 amount of water passing through the impeller I_1 at or above the amount necessary to produce full assistance to the ejector E .

While I have herein more particularly described a surface condenser, it will be understood that my invention is not limited thereto, except where so expressed in the claims, but that my improved apparatus is applicable also to other types of condenser, for example, jet condensers. 90

It will be understood that for either or both of the ejectors E and E_1 may be employed any other suitable type of ejector; or in lieu of them or either of them may be used other means for removing gas and uncondensable vapor from the condenser. 95

What I claim is:

1. Centrifugal water and air removing pump structure comprising coöperating impeller structures, means for delivering air 100 to the suction of one of said structures, means for delivering water to the suction of another of said structures, a water chamber, means for conducting water thereto, and passages in one of said impeller structures through which water from said water chamber is delivered into the other of said impeller structures. 105

2. Centrifugal water and air removing pump structure comprising coöperating impeller structures, means for delivering air 110 to the suction of one of said structures, means for delivering water to the suction of another of said structures, a water chamber, means for conducting water thereto, 115 and passages in the wall of the air impeller removing structure for delivering water from said water chamber into said other impeller structure.

3. Centrifugal water and air removing 120 pump structure comprising coöperating impeller structures, means for delivering air to the suction of one of said structures, means for delivering water to the suction of another of said structures, a water chamber, means for conducting water thereto, 125 and passages in one of said impeller structures through which water from said water chamber is delivered into the other of said impeller structures, the suction of said air 130

removing impeller structure consisting of a tubular extension extending through said water chamber.

4. Centrifugal water and air removing pump structure comprising coöperating impeller structures, means for delivering air to the suction of one of said structures, means for delivering water to the suction of another of said structures, a water chamber, means for conducting water thereto, and passages in the wall of the air removing impeller structure for delivering water from said water chamber into said other impeller structure, the suction of said air removing impeller structure consisting of a tubular extension extending through said water chamber.

5. Centrifugal water and air removing pump structure comprising coöperating impeller structures, means for delivering air to the suction of one of said structures, means for delivering water to the suction of another of said structures, a water chamber, means for conducting water thereto, 25 passages in one of said impeller structures through which water from said water chamber is delivered into the other of said impeller structures, the suction of said air removing impeller structure consisting of a tubular extension extending through said water chamber, and an air chamber communicating with said tubular extension.

6. Centrifugal water and air removing pump structure comprising coöperating impeller structures, means for delivering air to the suction of one of said structures, means for delivering water to the suction of another of said structures, a water chamber, means for conducting water thereto, 35 passages in the wall of the air removing impeller structure for delivering water from said water chamber into said other impeller structure, the suction of said air removing impeller structure consisting of a tubular extension extending through said water chamber, and an air chamber communicating with said tubular extension.

7. Centrifugal water and air removing pump structure comprising coöperating impeller structures, means for delivering air to the suction of one of said structures, means for delivering water to the suction of another of said structures, a water chamber, means for conducting water thereto, 45 passages in one of said impeller structures through which water from said water chamber is delivered into the other of said impeller structures, the suction of said air removing impeller structure consisting of a tubular extension extending through said water chamber, an air chamber communicating with said tubular extension, and air compressing means delivering into said air chamber.

8. Centrifugal water and air removing

pump structure comprising coöperating impeller structures, means for delivering air to the suction of one of said structures, means for delivering water to the suction of another of said structures, a water chamber, means for conducting water thereto, 70 passages in one of said impeller structures through which water from said water chamber is delivered into the other of said impeller structures, the suction of said air removing impeller structure consisting of a tubular extension extending through said water chamber, an air chamber communicating with said tubular extension, and an ejector delivering into said air chamber. 75

9. Centrifugal air and water removing pump structure comprising air and water removing impellers having independent suctions, said air removing impeller delivering into said water removing impeller, a 80 water chamber, means for delivering water thereto, and passages through a wall of said air removing impeller communicating with said water chamber and with said water removing impeller. 85

10. Centrifugal air and water removing pump structure comprising air and water removing impellers having independent suctions and each having vanes, said air removing impeller delivering into the spaces 90 between the vanes of said water removing impeller, a water chamber, means for delivering water thereto, and passages between the vanes of said impellers communicating with said water chamber and with 95 said water removing impeller. 100

11. The combination with a condenser, of centrifugal air and water removing pump structure comprising air and water removing impellers having independent suctions, 105 means for conducting air from the condenser to the suction of the air removing impeller, means for delivering condensate from the condenser to the suction of the water removing impeller, and means for 110 delivering water into said water removing impeller separately from said condensate.

12. The combination with a condenser, of centrifugal air and water removing pump structure comprising air and water removing impellers having independent suctions, 115 means for conducting air from the condenser to the suction of the air removing impeller, means for delivering condensate from the condenser to the suction of the 120 water removing impeller, a water chamber, means for delivering water from said water chamber separately from said condensate into said water removing impeller. 125

13. The combination with a condenser, of centrifugal air and water removing pump structure comprising air and water removing impellers having independent suctions, means for conducting air from the con- 130

denser to the suction of the air removing impeller, means for delivering condensate from the condenser to the suction of the water removing impeller, a water chamber, means for delivering water thereto, passages delivering water from said water chamber separately from said condensate into said water removing impeller, and means responsive to change in amount of condensate controlling admission of water into said water chamber.

14. The combination with a condenser, of centrifugal air and water removing pump structure comprising air and water removing impellers having independent suctions, an ejector delivering air from said condenser to the suction of said air removing impeller, means for delivering condensate from the condenser to the suction of the

water removing impeller, a water chamber, means for delivering water thereto, and passages delivering water from said water chamber separately from said condensate into said water removing impeller.

15. The combination with a condenser, of centrifugal air and water removing pump structure comprising air and water removing impellers having independent suctions, an ejector delivering air from said condenser to the suction of said air removing impeller, means for delivering condensate from the condenser to the suction of the water removing impeller, a water chamber, means for delivering water thereto, passages delivering water from said water chamber separately from said condensate into said water removing impeller, and means responsive to change in amount of condensate controlling admission of water into said water chamber.

16. The combination with a surface condenser, of a centrifugal pump for removing condensate therefrom, said pump comprising two impeller structures, one of said structures removing condensate and the other air from said condenser, a water chamber in said pump, means in said impeller forming passages communicating with said water chamber and with the interior of said impeller structure, and means responsive to decrease in condensate in said condenser for delivering water into said water chamber.

17. The combination with a surface condenser, of a centrifugal pump comprising air and condensate removing impellers having independent suctions, means for connecting the suction of said air removing impeller with the air space of said condenser, means for conducting condensate from said condenser to the suction of said water removing impeller, and means for delivering water separately from said condensate into the space between the vanes of said water removing impeller.

18. The combination with a surface con-

denser, of a centrifugal pump comprising air and condensate removing impellers having independent suctions, means for connecting the suction of said air removing impeller with the air space of said condenser, means for conducting condensate from said condenser to the suction of said water removing impeller, means for delivering water separately from said condensate into the space between the vanes of said water removing impeller, and means responsive to change in amount of condensate from said condenser controlling said water delivering means.

19. Centrifugal water and air removing pump structure comprising impeller structures, means for delivering air to the suction of one of said structures, means for delivering water to the suction of another of said structures, and means for delivering water to said other structure independently of said suction thereof.

20. Centrifugal water and air removing pump structure comprising air and water removing impellers having independent suctions, and means for delivering water to the water removing impeller independently of the water delivered to its suction inlet.

21. Centrifugal air and water removing pump structure comprising air and water removing impellers having independent suctions, said air removing impeller delivering into said water removing impeller, and means for delivering water into said water removing impeller independently of its suction inlet.

22. Centrifugal air and water removing pump structure comprising a casing, air and water removing impellers therein having independent suctions, a water chamber within said casing, and passages communicating with said chamber and with the water removing impeller independently of the suction inlet of said water removing impeller.

23. The combination with a condenser, of centrifugal air and water removing pump structure comprising air and water removing impellers having independent suctions, means for delivering water from said condenser to the suction of the water removing impeller, an air connection from said condenser to the air removing impeller, means for delivering water to the water removing impeller independently of the water delivered thereto from said condenser, and means responsive to change in amount of water from said condenser controlling the water independently delivered to said water removing impeller.

In testimony whereof I have hereunto affixed my signature this 17th day of December, 1917.

ROBERT SUCZEK.
